US0D1084306S

(12) **United States Design Patent** (10) **Patent No.:** **US D1,084,306 S**
(45) **Date of Patent:** **** Jul. 15, 2025**

(54) **HANDHELD DRUG DELIVERY DEVICE**

(71) Applicant: **AMGEN INC.**, Thousand Oaks, CA (US)

(72) Inventors: **Peter Dan Kaare Soelberg**, Gentofte (DK); **Kasper Poder**, Tikøb (DK); **Rasmus Ohlenschlager**, Hellerup (DK); **Dylan Bourelle**, Casstown, OH (US)

(73) Assignee: **AMGEN INC.**, Thousand Oaks, CA (US)

(**) Term: **15 Years**

(21) Appl. No.: **29/937,871**

(22) Filed: **Apr. 17, 2024**

Related U.S. Application Data

(62) Division of application No. 29/720,554, filed on Jan. 14, 2020, now Pat. No. Des. 1,030,040.

(57) **CLAIM**

The ornamental design for a handheld drug delivery device as shown and described.

DESCRIPTION

FIG. 1 is a perspective view showing a new design for a handheld drug delivery device;

FIG. 2 is a front view of the handheld drug delivery device of FIG. 1;

FIG. 3 is a rear view of the handheld drug delivery device of FIG. 1;

FIG. 4 is a right-side view of the handheld drug delivery device of FIG. 1;

FIG. 5 is a left-side view of the handheld drug delivery device of FIG. 1;

FIG. 6 is a top view of the handheld drug delivery device of FIG. 1;

FIG. 7 is a bottom view of the handheld drug delivery device of FIG. 1;

FIG. 8 is a perspective view of the handheld drug delivery device of FIG. 1 with its cap removed; and,

FIG. 9 is a top view of the handheld drug delivery device of FIG. 1 with its cap removed.

The broken lines show portions of the handheld drug delivery device that form no part of the claimed design.

1 Claim, 5 Drawing Sheets
